UNITED STATES PATENT OFFICE.

CARL BRUNO DOLGE, OF DOLGEVILLE, ASSIGNOR TO ALFRED DOLGE, OF NEW YORK, N. Y.

MANUFACTURE OF HAIR-FACED WOOL FELT.

SPECIFICATION forming part of Letters Patent No. 314,810, dated March 31, 1885.

Application filed December 11, 1884. (No model.)

To all whom it may concern:

Be it known that I, CARL BRUNO DOLGE, a citizen of the United States, residing at Dolgeville, in the county of Herkimer and State of New York, have invented new and useful Improvements in the Manufacture of Hair-Faced Wool Felt, of which the following is a specification.

This invention relates to felt made of wool and faced on both sides with hair.

In the accompanying drawings, Figure 1 represents a side elevation of a carding-machine. Fig. 2 is a plan view of the feed-table of said carding-machine on a larger scale than the previous figure. Fig. 3 is a transverse section of a pile of webs formed for producing hair-faced felt with a rectangular cross-section. Fig. 4 is a transverse section of a pile of webs for producing hair-faced felt with a tapering cross-section. Fig. 5 is a transverse section of the tapering felt when complete.

Similar letters indicate corresponding parts.

In order to produce hair-faced felt of a rectangular cross-section I proceed as follows: I spread on the feed-table A of the carding-machine a quantity of hair, distributing the same evenly over the entire width of the table, (or to a width corresponding to the width of the fabric to be produced,) and after this first layer, a, of hair has passed through the carding-machine it is taken from said carding-machine by an endless apron, which moves with a velocity equal to the speed at which the material to be felted passes through the card, and which conveys the carded material—the so-called "web"—to another apron that runs direct between the rollers of a felting-machine. Before all the material of the web a is worked up by the carding-machine and conveyed to said endless apron a layer of wool, a', of the same width as the first layer, is then evenly spread on the feed-table of the carding-machine, and is in the same manner worked and conveyed to the endless aprons, which likewise carry this wool web a' to the felting-machine, the rollers of which are continually in operation, thus felting the wool web a' directly onto the hair web a. When the wool web a' has fully covered the hair web a, a series of layers of wool are

spread in like manner consecutively on the said feed-table and worked and conveyed to the felting-machine, as above described, and this operation I continue, adding wool webs a' a' to a', and finally another hair web, a', in accordance with the required thickness of the fabric.

In order to produce hair-faced wool felt with a tapering cross-section I first produce in like manner as above a hair web, a, Fig. 4, equal in width to the width of the fabric to be produced. Then I produce a woolen web, a', of equal width and length, and felt the same together with the hair web a. Then I produce a compound web, a'', partly of hair, h, and partly of wool, w, (which can be effected by placing upon the feed-table A, near one side, a narrow strip of hair and filling up the rest with wool,) and felt this compound web together with the webs previously felted. Then I produce another compound web, a''', (composed of hair, h, and wool, w,) of less width than the previous webs, and felt the same together with the webs previously felted, until I arrive at the web a'', which is the narrowest, and which is made entirely of hair. By felting together all the webs above named a felt is produced which is tapering in cross-section and faced with hair on both sides, Fig. 5. The same result may be obtained by first producing the narrowest web and have the others increase in width—the reverse way as described above.

By facing wool felt with hair a fabric is obtained which is of great advantage for many purposes—such, for instance, as for the hammers of piano-fortes, where it is desirable to combine the elasticity of the wool felt with the hardness and toughness of the hair felt.

I am aware that a compound fabric of felt, cloth, and hair has heretofore been made by taking a piece of burlap and, through the medium of a felting-machine, throwing thereupon a stratum or sheet of felt, the two being united by felting, a stratum or series of strata of hair being subsequently affixed to the fabric, as in Patent No. 49,353. Such therefore I disclaim.

My invention differs from the prior fabric in that I first card a layer of hair and then card on the hair fabric a layer or layers of wool,

and then felt the wool and hair layers together, a final covering of hair being added in the same manner.

What I claim as new, and desire to secure by Letters Patent, is—

1. The method herein described of making hair-faced wool felt, which consists in first carding a layer of hair, then carding a layer or layers of wool, and then felting the wool and hair layers together, substantially as described.
2. The method herein described of making hair-faced wool felt, which consists in first carding a layer of hair, then carding a layer or layers of wool, adding a final layer of hair, and 15 felting the layers together to form wool felt

faced on opposite sides with hair, substantially as described.

3. As a new article of manufacture, wool felt faced with hair, as shown and described.

4. As a new article of manufacture, wool felt 20 having a tapering cross-section and faced on both sides with hair, as described.

In testimony whereof I have hereunto set my hand and seal in the presence of two subscribing witnesses.

CARL BRUNO DOLGE. [L. S.]
